Patented Feb. 27, 1962

192,308

COMBINED CLIP BOARD AND LIGHT

George J. Cory, 1722 Archwood Ave., North
Hollywood, Calif.

Filed Jan. 11, 1961, Ser. No. 63,541

Term of patent 14 years

(Cl. D74—2)

Fig. 1.

Fig. 2.

Fig. 3.

Fig. 4.

Fig. 5.

Fig. 6.

FIG. 1 is a top plan view of a combined clip board and light showing my new design;

FIG. 2 is a left side elevational view thereof;

FIG. 3 is a front elevational view;

FIG. 4 is a bottom plan view;

FIG. 5 is a right side elevational view thereof; and

FIG. 6 is a rear elevational view thereof.

I claim:

The ornamental design for a combined clip board and light, as shown.
